UNITED STATES PATENT OFFICE.

WILLIAM E. KNOWLES, OF OAKLAND, CALIFORNIA.

ELECTRIC-CURRENT-DISPENSING DEVICE.

Application filed June 29, 1925. Serial No. 40,353.

My invention relates to improvements in dispensing devices for electric current wherein the insertion of a token will operate to close a primary circuit between a source of energy and a point of consumption to permit the use of electric current for a measured period after which the circuit will be automatically disconnected to prevent further use of the current until another token is inserted.

The primary object of my invention is to provide an improved device for dispensing electric current for measured periods.

Another object is to provide an improved device which may be conveniently transported from place to place and installed for temporary service as required.

Another object is to provide an improved device which is operated by the insertion of a token to positively close a circuit for a predetermined period and to automatically break the circuit when the period of time has elapsed.

A further object is to provide an improved device wherein timing mechanism is positively started simultaneously with the closing of the circuit and positively stopped and held against movement when the circuit is broken.

Another object is to provide an improved arrangement wherein a secondary circuit is induced from the primary circuit being dispensed and arranged to supply energy for automatically breaking the primary circuit and stopping the timing mechanism at the end of a predetermined period.

A further object is to provide a device of improved construction wherein a single movable armature is utilized for controlling the primary circuit and the timing mechanism, and also for breaking the secondary circuit.

A still further object is to provide a device of the character described which is simple in construction, and efficient in operation, and which can be economically manufactured and used.

I accomplish these and other objects by means of the device disclosed in the drawings forming a part of the present specification wherein like characters of reference are used to designate similar parts throughout said specification and drawings and in which,

Fig. 1 is a front elevation of my improved electric current dispensing device with the front housing cover opened to show the operating mechanism.

Fig. 2 is a vertical transverse section through the housing showing the mechanism therein in elevation.

Fig. 3 is a front elevation of the coin control mechanism.

Fig. 4 is a horizontal section through the housing showing a plan of the operating mechanism.

Fig. 5 is a broken detail view showing the operation of the secondary current relay and the armature.

Fig. 6 is a detail of the starting arm.

Fig. 7 is a conventional wiring diagram of the device.

Fig. 8 is an enlarged detail showing the manner in which the timing mechanism is controlled.

Fig. 9 is a sectional detail of the coin inserting means.

Referring to the drawings, the numeral 1 is used to designate in general a housing having a hinged mounted front cover 2 arranged to be locked in any suitable manner to normally close the housing. A bushing 3 is mounted in the top of the housing to admit conductors 4 and 5 forming feed and return wires to a source of electrical energy, not shown.

The conductors 4 and 5 are connected to contacts arranged to be engaged by the poles of a two pole switch 6 to which are connected conductors 7 and 8. The conductor 8 is connected to a contact 11 adapted to be engaged by a movable contact 9 connected to a conductor 12. The conductor 7 forms one side of circuit to a point of consumption, not shown, the other side of said circuit being formed by the conductors 8 and 12 connected through the contacts 9 and 11 to close or break the circuit as hereinafter more fully explained. The conductors 7 and 12 are carried outwardly from the housing 1 through a bushing 13 and extended to a motor or other device not shown to be operated.

The switch 6 is mounted upon brackets 14 secured upon a panel 16 formed of suitable insulating material and detachably secured within the back of the housing 1 by means of suitable securing elements 17. An operating button 18 for the switch 6 extends out-

wardly through a slot 19 in the front cover 2 of the housing whereby the switch may be manually operated to break the circuit if desired.

5 The contact 9 is mounted upon a pivotally movable armature 21 adapted to be moved to carry the contact 9 into engagement with the contact 11 to close the primary circuit therebetween, and to carry said contact 9 out 10 of engagement with the contact 11 to break the circuit. The contact 9 preferably consists of a metallic pin adapted to be frictionally engaged by a socket member constituting the contact 11, said socket contact being adapted to exert a spring pressure upon the pin to normally hold the contacts in contacting relation.

The armature 21 is provided with an arm 22 adapted to be engaged by a token or a 20 coin 23 of a particular denomination and to be moved thereby to carry the armature and the contact 9 to circuit closing position. To accomplish this the arm is shaped to extend through a slot 24 formed in the 25 side of a chute 26 mounted within the housing 1 and provided with an enlarged upper portion 27 opening immediately below a coin slot 28 formed in the top of the housing whereby a coin inserted 30 through the slot 28 will drop down the chute 26 and be intercepted by the arm 22. A plunger 29 is slidably mounted upon a bracket 31 secured upon the front of the chute 26. The lower end of the plunger is 35 offset as at 32 and the upper end is provided with an actuating member 33 extending outwardly through the top of the housing 1 whereby the plunger may be depressed against the tension of a spring 34 connected 40 between the plunger and the bracket to normally hold said plunger in its uppermost position as shown in Fig. 3 of the drawings. The offset portion of the plunger is so arranged that when the plunger is depressed 45 the plunger will be moved inwardly through a slot 36 formed in the front of the chute 26 to engage the coin 23 and move the same downwardly past the arm 22 as shown in dotted lines in Figs. 3 and 9 of 50 the drawings. The movement of the coin downwardly past the arm 22 causes said arm to be displaced and the armature 21 to be swung pivotally as shown in dotted lines in Fig. 3, the contact 9 being thereby 55 carried into engagement with the contact 11 to close the circuit therebetween. The movement required to carry the contact 9 into frictional engagement with the contact 11 is arranged to be such that a coin of smaller 60 denomination than that for which the machine is designed will not cause the armature and contact to be fully moved to circuit closing position and the armature will be returned to normal position by a spring 65 37 and thereby prevent the closing of the

primary circuit. After the coin 23 has passed the arm 22 it drops into a suitable receptacle 38 placed in the housing 1 below the chute 26.

The armature 21 is mounted in operative 70 relation to a relay 39 mounted upon the panel 16 and arranged to be energized by a secondary circuit to attract the armature when the secondary circuit is closed and thereby move the armature and the contact 75 9 carried thereby to break the primary circuit. The secondary circuit is preferably induced by a transformer 40 having its primary terminals connected into the primary circuit through conductors 41 and 42 80 connected directly to the conductors 4 and 5, at the switch 6. The secondary terminals of the transformer receive conductors 43 and 44, one of which is connected to a flat spring member 46 while the other is 85 connected through the relay 39 and a conductor 47 to a contact point 48 spaced from the contact member 46, the secondary circuit being normally broken between said contact member 46 and the point 48. 90

The secondary circuit is arranged to be closed between the member 46 and the contact point 48 by means of a contact arm 49 arranged to be moved at a calculated rate to automatically close said circuit at 95 a predetermined time after the primary circuit has been closed as above explained. This is accomplished preferably by means of a clock mechanism consisting of a train of gears designated in general by the numeral 51, said gears being mounted within a suitable frame 52 and actuated by means of a clock spring 53 in the well known manner. The contact arm 46 is mounted upon an outward extension of a shaft 54 adapted to cause the arm to make one complete revolution in a desired period of time. In my preferred construction illustrated in the drawings, the shaft 54 corresponds to the minute hand shaft of the clock so that the 100 arm 49 will be moved through one complete revolution in a period of one hour, the arm being mounted upon what would ordinarily be considered the back of the clock so that the arm is moved in a counter 105 clockwise direction. As the arm is moved by the clock mechanism, the outer end of the arm is caused to engage the spring contact member 46 and form electric contact therewith, said arm being made of suitable 110 conductive material insulated from the clock mechanism by means of a suitable block of insulating material 56. A contact point 57 is secured upon the extreme outer end of the arm 49 and arranged to engage and 115 form electrical connection with the contact point 48 at a predetermined point of time, thereby closing the secondary circuit and causing the relay 39 to be energized. 120

The clock mechanism 51 is controlled and 125

caused to operate in conjunction with the armature 21 by means of a control arm 58 rigidly secured upon the armature and adapted to engage the shaft 59 to balance wheel 61 forming a part of the clock mechanism as in the ordinary clock construction. The outer end of the arm 58 is arranged at substantially right angles to the shaft 59 and is provided with casing 62 formed of rubber or other resilient material adapted to contact with the shaft. When the armature is in its normal circuit breaking position the control arm 58 is held with the casing 62 pressed against the shaft 59 as best shown in the enlarged detail shown in Fig. 8 of the drawings. In this position sufficient pressure is exerted against the shaft 59 to prevent the operation of the balance wheel 61 and the operation of the clock mechanism is thus prevented.

When the armature 21 is moved as above explained to close the primary circuit between the contacts 9 and 11, the control arm 58 is moved to the position indicated in dotted lines in Fig. 8, the forward movement of the arm and the frictional engagement between the casing 62 and the shaft 59 operating to impart a starting impulse to said shaft 59 and the balance wheel carried thereby, in this manner starting the clock mechanism into operation at the instant the primary circuit is closed.

In order to break the secondary circuit after the relay has operated to break the primary circuit, the arm 22 is provided with an extension 63 extending past the contact arm 46 as best shown in Figs. 5 and 6 of the drawings. The extension is bent inwardly at its outward end and arranged to be sprung slightly to permit the movement of the contact arm therest past the contact point 48 the contact point 48. A notch 64 is formed upon the side of the extension adjacent the contact arm 46 to engage the side of said arm. When the armature 21 is moved to break the circuit, the arm is moved and the notch 64 caused to engage the edge of the contact arm 46 and move said arm past the contact point 48, in this manner insuring the breaking of the secondary circuit and causing a quick break between the contact points 48 and 57 whereby an arcing and burning of the points is prevented.

My improved dispensing device is intended primarily for rental purposes in connection with washing machines, or other electrically driven devices to be used for relatively short periods of time. In this connection the dispensing device is arranged to be connected directly between a source of energy and the motor of the machine so that power cannot be delivered to the machine until the primary circuit through the dispensing device has been closed by the insertion of a coin, or token and that after the

primary circuit has been so closed the power may be freely used during a predetermined period after which the secondary circuit is closed to automatically break the primary circuit and prevent the further use of power until another coin has been inserted. In this connection the operation of my improved device is as follows:

The machine or device to be operated is set up and prepared for use in the ordinary manner and connection made through the dispensing device to a source of power. When it is desired to turn on the flow of electricity a token or a coin of the prescribed denomination is dropped into the chute 26 and the plunger 29 depressed to force the coin past the arm 22 and thereby move the armature pivotally about its mounting until the contact 9 is moved into circuit closing relation with the contact 11. The same movement of the armature that effects the closing of the circuit moves the clock control arm 58 to impart a starting impulse to the clock mechanism so that said mechanism is set in motion and the contact arm 46 thereby moved at the calculated rate to close the secondary as above explained. At the moment the secondary circuit is closed between the contact arm 46 and the contact point 48 the relay 39 is energized and the armature 21 moved to break the primary circuit between the contacts 9 and 11. This same movement of the armature operates to move the control arm 58 into engagement with the balance wheel shaft 59 thereby stopping the clock mechanism and preventing further operation thereof until the primary circuit is again closed and said clock mechanism started by the insertion of another coin. The movement of the armature also causes the extension 63 of the arm 22 to engage the contact arm 46 and move the same past the contact point 48, thereby breaking the secondary circuit.

The switch 6 may be operated manually entirely independently of the automatic circuit closing and breaking elements of the device so that the primary circuit may be turned on or off at will during the period for which the device is set in operation.

The period of time and the denomination of coin for which the device is designed may of course be varied to conform to the purpose for which the current is intended to be used. Thus if the average usage for which the device is intended to be rented is one hour the contact arm is arranged to be moved through a full rotation in just an hour of time and the coin required to set the device in operation is calculated to meet the normal consumption of power during that period. Longer or shorter periods of time may of course be used if desired. The clock mechanism is wound at intervals as required in the ordinary manner and the

coins inserted into the device are collected at the convenience of the person renting the device.

The cover 2 of the housing 1 is formed from sheet metal and arranged to be locked to effectually close the front of the housing so as to prevent access by unauthorized persons. The chute 26 is enlarged at the top and the slot is sufficiently offset from the main vertical portion of the chute to prevent the insertion of an object adapted to displace the armature to operative position without inserting the required coin, in this manner guarding against the unlawful operation of the machine.

The several elements are mounted in compact arrangement within the housing so that the entire device may be made of relatively small size so as to be conveniently transported from place to place as required and installed in connection with various machines or for various purposes as required. In service the device is so coordinated in action as to obtain a positive and efficient operation in opening and closing the primary circuit and in limiting the dispensing operation to an accurately regulated period of time.

Having thus described my invention what I claim as new and desire to secure by Letters Patent is,

1. An electric current dispensing device comprising the combination with a primary circuit adapted to conduct electricity from a source to a point of consumption, of a pair of contacts mounted within said circuit, one of said contacts being movable to open and close the circuit; means for moving the movable contact to circuit closing position; a secondary circuit associated with the primary circuit and deriving power therefrom; a relay adapted to be energized by the secondary circuit for moving the movable contact to break the primary circuit; a contact arm movable to open and close the secondary circuit; actuating means for moving the contact arm at a calculated rate; and means operated by the relay in conjunction with the movable contact for starting the actuating means when the contact is moved to circuit closing position and to stop said actuating means when the contact is moved to circuit breaking position when the contact arm has been moved to close the secondary circuit after a predetermined lapse of time; and means actuated in conjunction with the movable contact for moving the contact arm out of secondary circuit closing position.

2. An electric current dispensing device comprising the combination with a primary circuit adapted to conduct electricity from a source to a point of consumption, of a pair of contacts mounted in connection with said circuit, one of said contacts being movable to open and close the circuit; means for mov-

ing the movable contact to circuit closing position; a secondary circuit; a relay adapted to be energized by the secondary circuit for moving the movable contact to break the primary circuit; a contact arm movable to open and close the secondary circuit; actuating means for moving the contact arm at a calculated rate; and means operated by the relay in conjunction with the movable contact for starting the actuating means when the contact is moved to circuit closing position and to stop said actuating means when the contact is moved to circuit breaking position after the contact arm has been moved to close the secondary circuit after a predetermined lapse of time.

3. An electric current dispensing device comprising the combination with a primary circuit adapted to conduct electricity from a source to a point of consumption, of a pair of contacts mounted in connection with said circuit, one of said contacts being movable to open and close the circuit; a secondary circuit; a relay connected into the secondary circuit and adapted to be energized thereby; a pivotally movable armature mounted adjacent the relay and adapted to actuate the movable contact; a contact arm movable to open and close the secondary circuit; actuating means for moving the contact arm at a calculated rate; a control arm connected to the armature and movable therewith for starting the actuating means when the movable contact is moved to close the primary circuit and to stop said actuating means when the contact is moved to circuit breaking position after the contact arm has been moved to close the secondary circuit after a predetermined lapse of time.

4. An electric current dispensing device comprising the combination with a primary circuit adapted to conduct electricity from a source to a point of consumption, of a pair of contacts mounted in connection with said circuit, one of said contacts being movable to open and close the circuit; a secondary circuit; a relay connected into the secondary circuit and adapted to be energized thereby; a pivotally movable armature mounted adjacent the relay and adapted to actuate the movable contact; a contact arm movable to open and close the secondary circuit; actuating means for moving the contact arm at a calculated rate; a control arm connected to the armature and movable therewith for starting the actuating means when the movable contact is moved to close the primary circuit and to stop said actuating means when the contact is moved to circuit breaking position after the contact arm has been moved to close the secondary circuit after a predetermined lapse of time; and a member connected to the armature and movable therewith for moving the contact arm out of circuit closing position in the secondary circuit.

5. An electric current dispensing device comprising the combination with a primary circuit adapted to conduct electricity from a source to a point of consumption, of a pair of contacts mounted in connection with the circuit, one of said contacts being movable to open and close the circuit; a secondary circuit; a relay arranged to be energized by the secondary circuit; a pivotally movable armature mounted adjacent the relay and arranged to be actuated thereby, said armature being connected to the movable contact for moving said contact to circuit closing and breaking positions; means connected to the armature for moving the armature to carry the contact to circuit closing position; a contact arm movable to open and close the secondary circuit; clock mechanism arranged to move the contact arm at a calculated rate; and a clock control arm mounted upon the armature and movable therewith to impart a starting impulse to the clock mechanism when the movable contact is moved by the armature to close the primary circuit and to stop and prevent further operation of the clock mechanism when the contact is moved by the armature to circuit breaking position after the contact arm has been moved by said clock mechanism to close the secondary circuit after a predetermined lapse of time.

6. An electric current dispensing device comprising the combination with a primary circuit adapted to conduct electricity from a source to a point of consumption, of a pair of contacts mounted in connection with the circuit, one of said contacts being movable to open and close the circuit; a secondary circuit; a relay adapted to be energized by the second circuit; a pivotally movable armature mounted adjacent the relay and adapted to be actuated thereby when the relay is energized, said armature being connected to the movable contact for moving said contact to circuit closing and opening positions; means connected to the armature for moving the armature to carry the contact to circuit closing position; a contact arm movable to open and close the secondary circuit; a clock mechanism, including a balance wheel for moving the contact arm at a calculated rate; and a clock control arm mounted upon the armature and movable therewith to impart a starting impulse to the balance wheel of the clock mechanism when the movable contact is moved by the armature to close the primary circuit, and to stop the balance wheel and prevent further operation of the clock mechanism when the contact is moved by the armature to circuit breaking position after the contact arm has been moved by the clock mechanism to close the secondary circuit after a predetermined lapse of time, and thereby energize the relay to move said armature.

7. In an electric current dispensing device comprising a primary and a secondary circuit, said secondary circuit including a relay and armature movable thereby for breaking the primary circuit, of a pair of spaced contacts connected to opposite terminals of the secondary circuit and normally breaking said circuit; a rotatable contact arm adapted to bridge said contacts to complete the secondary circuit; and actuating means for moving the contact arm at a calculated rate whereby the secondary circuit may be completed and the primary circuit broken after a predetermined lapse of time; and means engaging the contact arm and actuated by the movement of the armature for moving said contact arm out of engagement with the contacts when said armature is moved to break the primary circuit.

8. In an electric current dispensing device comprising a primary and a secondary circuit, said secondary circuit including a relay and armature movable thereby for breaking the primary circuit, of a pair of spaced contacts connected to opposite terminals of the secondary circuit and normally breaking said circuit; a rotatable contact arm adapted to bridge said contacts to complete the secondary circuit; and actuating means for moving the contact arm at a calculated rate whereby the secondary circuit may be completed and the primary circuit broken after a predetermined lapse of time; and means engaging the contact arm and actuated by the movement of the armature for moving said contact arm out of engagement with the contacts when said armature is moved to break the primary circuit.

9. In an electric current dispensing device comprising a primary circuit and a secondary circuit, said secondary circuit including a relay and an armature movable thereby for breaking the primary circuit, of a rotatable contact arm movable for closing the secondary circuit to energize the relay, and a clock mechanism mounted in connection with the contact arm to move the same at a calculated rate, said mechanism including a balance wheel; and a clock control arm mounted in connection with the armature and adapted to engage the balance wheel shaft of the clock mechanism, said arm being movable to impart a starting impulse to the balance wheel and thence to the clock mechanism when the armature is moved to close the primary circuit, and to stop said balance wheel and prevent further movement of the clock mechanism when the armature is moved to break the primary circuit.

10. An electric current dispensing device comprising the combination with a primary circuit adapted to conduct electricity from

a source to a point of consumption, of a pair of contacts mounted within the circuit, one of said contacts being movable to make and break said circuit; means for moving the 5 movable contact to close the circuit; a secondary circuit; relay controlled means operated by the secondary circuit for breaking the primary circuit; a contact arm movable to open and close the secondary circuit; actuating means for moving the contact arm 10 at a calculated rate; and means operated in

conjunction with the movable contact for controlling said actuating means, whereby said actuating means is started when the movable contact is moved to circuit closing 15 position and the contact arm moved to close the secondary circuit after predetermined lapse of time and thereby break the primary circuit and stop the actuating means.

In witness whereof I hereunto set my sig- 20 nature.

WILLIAM E. KNOWLES.
